ARTHUR G. CHAPMAN, OF UPPER MONTCLAIR, NEW JERSEY, ASSIGNOR TO AMERICAN TELEPHONE AND TELEGRAPH COMPANY, A CORPORATION OF NEW YORK

WAVE-ANTENNA ARRAY

Application filed August 23, 1928. Serial No. 301,612.

This invention relates to radio receiving systems and particularly to an antenna system employing a plurality of wave antennæ staggered longitudinally, the said antennæ being so arranged and connected that the currents set up in certain of said antennæ by waves from an undesired direction may be opposed to the current set up by the same waves in another of said antennæ and thus neutralized.

Wave antennæ are well known in the art, having been disclosed in the patents to Beverage and others, and in technical publications. A radio receiving system, consisting of two parallel like wave antennæ separated by a fraction of a wave length and with one antenna displaced longitudinally a fraction of a wave length with respect to the other, has been called a staggered system. The antennæ must be separated 1,000 to 1,200 feet apart to minimize crosstalk between them and each antenna requires a pole line for its support and a transmission line to bring the received currents to the radio receiver. Furthermore, the separation of the antennæ produces a broadside effect, that is the effect of space phase change from one antenna to the other in undesired waves received from points not in line with the antennæ in either direction, which effect must be taken into consideration.

In my copending application Serial No. 235,303, filed November 23, 1927, is described the staggered wave antenna system comprising two antennæ placed on a single pole line and so arranged that no crosstalk exists between the antennæ. The system described in the said copending application does not have a sharp directional characteristic, it being capable of receiving a fairly large percentage of current at an angle as great as 90 degrees from the desired direction.

The present invention resides in a system employing three wave antennæ so arranged and connected that the currents from undesired waves in two of said antennæ may oppose and neutralize the current from the same undesired waves in the third antenna thereby giving to the entire antenna system a sharp receiving characteristic.

This invention will be clearly understood

from the following description when read in connection with the attached drawing of which Figure 1 shows schematically a form of the embodiment of the invention; Fig. 2 which in general is similar to Fig. 1 shows in greater detail the mode of connecting the antennæ; Figs. 3a, 3b, 3c and 3d are curves and vector diagrams illustrating the principle underlying the invention and Figs. 4, 5, 6 and 6a show the manner in which the antenna system employing this invention may be set up on a single pole line.

In Fig. 1, 1, 2 and 3 represent three wave antennæ which are parallel and staggered a predetermined distance. Thus the antenna 2 is staggered a distance of $2d$ with respect to antenna 1 and antenna 3 is staggered a distance of d with respect to antennæ 1 and 2. Three like transmission lines 4, 5 and 6 connect antennæ 1, 3 and 2 with the combining and receiving apparatus. In practice, the lines would have different lengths but would be compensated by artificial lines and attenuators to have effectively the same length as indicated schematically in Fig. 1. The ends of antennæ 1 and 2 are connected by transmission lines 4 and 6 with a network HC_1 , which network serves to combine the currents from the antennæ 1 and 2. While various types of combining networks may be employed, a preferred form is that disclosed in Fig. 2 of the drawing filed with the application of Bailey and Dean, Serial No. 183,532, filed April 13, 1927. The transmission line 6 contains an artificial line N_1 for retarding the phase of the current being transmitted from the antenna 2 to the network HC_1 prior to impressing the said current upon the network. The output of HC_1 is connected with the combining network HC_2 , the connection including an attenuator A_1 to suitably reduce the current transmitted from the network HC_1 to the network HC_2 and a transmission to reverse the phase of the current entering HC_2 . The antenna 3 is also connected with the network HC_2 through an artificial line N_2 , which retards the phase of the current transmitted from antenna 3 to network HC_2 . The output of the network

HC_2 may be connected with any form of receiving apparatus indicated by R . It will be apparent that the currents set up in the antennæ of the array by any source extraneous thereto will be combined and impressed upon the receiving device connected therewith. The manner in which the currents combine and the degree of neutralization that will be effected depends upon the proper location of the antennæ and the amount of staggering. It is necessary to so locate the antenna array that its longitudinal axis points toward the station from which it is desired to receive signals. The antenna system and associated artificial lines and attenuators are then arranged so as to produce zero reception from certain directions and a minimum from directions other than that from which it is desired to receive signals.

Let it be assumed that it is desired to receive zero current from a direction at an angle Θ equal to 180 degrees removed from the direction of the desired signal. The staggering distance d and the phase change in artificial line N_1 are so chosen that when Θ equals 180 degrees, the currents x and y are in phase. Those currents will be added and the resultant will, of course, be twice that of each separate antenna. Since that current is to be used to neutralize the current set up by the same wave in antenna 3, it must be reduced one-half in network HC_1 and attenuator A_1 in order to effect neutralization. The resultant current, namely

$$\frac{y+x}{2},$$

is then reversed in phase by a transposition and impressed upon the network HC_2 together with the current z which is transmitted from the antenna 3 over the transmission line 5 and changed in phase by artificial line N_2 to bring it in phase with y and x . By opposing those currents in the network HC_2 , neutralization is obtained of current resulting from waves striking the antenna system from a direction 180 degrees from the desired direction. For this direction, the currents entering HC_2 are in opposite phase at all frequencies if the phase changes of artificial lines N_1 and N_2 increase directly as the frequency. The array characteristic, i. e., the ratio of the magnitude of current w to that of current z , is shown in Fig. 3a. In computation, the staggering distance was chosen to be $1/8$ wavelength for the frequency of the desired signal and the null point was chosen at 180 degrees. By varying the artificial lines N_1 and N_2 , a null point (at all frequencies) may be caused to occur at some other angle. Fig. 3a also shows the array characteristic for $d=1/8$ wave length and a null point at 160°. For $d=1/8$ wave length for the frequency of the

desired signal and a null point at 180 degrees the vector diagrams of Figs. 3b, 3c and 3d show the phase relations of current z , x and y and also the phase relations of

$$-\frac{x+y}{2} \text{ and } z.$$

The diagrams are given for $\Theta=0, 90$ and 180 where Θ is the angle between the direction of an undesired signal and that of the desired signal.

Fig. 2 shows how the individual antennæ of Fig. 1 would be terminated and coupled with transmission lines in order to contain the desired combination of currents.

The diagrams of the #3 group of figures assume no lateral spacing between the three antennæ. If a system were actually constructed in accordance with Figs. 1 and 2, it would be necessary to use appreciable lateral spacing between the antennæ to avoid crosstalk between them unless the antenna length were equal to or less than d . This lateral spacing improves the array factor from $\theta=0$ to $\theta=180^\circ$ and degrades it from $\theta=180^\circ$ to $\theta=360^\circ$. The effect may be reversed by interchanging antennæ 1 and 2. For example, for a lateral spacing between adjacent antennæ of $1/8$ th wave length, the array characteristic is changed from .29 to .077 at $\theta=90^\circ$ and from .29 to .62 at $\theta=270^\circ$. For angles near zero or 180° the array factor is little dependent on the lateral spacing. If the undesired signals come mostly from one side of the array, the distortion of the array factor, due to lateral spacing, is not objectionable. To avoid this distortion, and avoid the use of three separate pole lines a special antenna shown in Fig. 4 may be used instead of the simple antennæ 1, 2 or 3 of Figs. 1 and 2. Such an antenna would have about the same directional characteristics as the simple antenna and about one half the strength of desired signal. The special antenna consists of a series of short antennæ each of length d and spaced longitudinally at distances d . The short antennæ are connected to a combining network HC_3 through like transmission lines and through artificial lines N_3 to N_6 to change the phases of the individual currents. The phase changes of these lines are adjusted to bring the four currents entering HC_3 into phase for the value of θ at which is desired to have a null point. If three such special antennæ are arranged as in Fig. 1, it will be seen that the last three sections of the upper antenna and the first three sections of the lower antenna are unnecessary since the currents from these sections are mutually cancelling in network HC_1 for all values of θ . The array of three antennæ may therefore be replaced by the arrangement of Fig. 5. The short antennæ of Fig. 5 may all be placed on a single pole

line. Furthermore, if each antenna consists of several metallic pairs in multiple with ground return, the metallic pairs may be used for the transmission lines, as indicated in Fig. 6. With this arrangement, the transmission lines would be compensated by terminal artificial lines and attenuators to have the same total phase change and attenuation. By using six pairs, the signals from the individual short antennæ may be transmitted to the end of the line nearest the station sending the desired signal. This has the advantage that much smaller values of phase change need to be supplied by the local artificial lines. The metallic pairs must, of course, be carefully transposed to avoid crosstalk between them.

The arrangement shown in Fig. 6 provides a system of conductors that are capable of intercepting the radio waves and of transmitting to the terminal apparatus the currents created thereby. Such terminal apparatus would be similar to that shown in Figs. 5 and 1. The arrangement in Fig. 6 comprises five pairs of wires that may be supported upon the crossarms on a single pole line. Each pair of wires is sectionalized in a manner corresponding to the six short antennæ and three intervening spaces of Fig. 5. All of the wires in each section corresponding to a short antenna of Fig. 5 are grounded at one end through a resistance representing the characteristic impedance of the five transposed pairs with ground return and at the other end through the winding of a transformer, the other winding of which is connected across one of the pairs of wires of the succeeding section. Thus, for example, all of the conductors of the section AB are connected at the right-hand side with a winding of a transformer, the other winding of which is connected across the conductors of pair 1 in the section BC. It will be seen that by means of transformers at the section junction points, the current set up in all the wires of section AB and transmitted into pair 1 in the section BC will be transmitted over the successive sections of that pair to the output of the final transformer at the right-hand side and from there to the left-hand artificial line N_3 of Fig. 5. In like manner, all of the conductors of the section BC are connected to ground at both ends, the right-hand connection including a winding of a transformer, the other winding of which is connected across pair 2 in the section CD. Current set up in all the wires of section BC will be transmitted along pair 2 to the right to the terminal apparatus at that end. In like manner the current set up in all of the conductors of the sections DE, FG, and HI will be transmitted to the right over wires 3, 4 and 5, respectively. Current set up in all of the conductors of section IJ

which is the right-hand terminal section will be connected directly with the terminal apparatus. From the foregoing description it will be apparent that the arrangement shown in Fig. 6 provides a sectionalized antenna system that is capable not only of intercepting the electromagnetic waves but is also capable of transmitting to the terminal apparatus the currents resulting from such interception. The arrangement shown in Fig. 6 when the six pairs of terminals at the right are connected to the six artificial lines N_3 to N_6 , shown in Fig. 5, will function in the same manner as the arrangement shown in Fig. 1.

It is to be understood that while the invention has been disclosed in certain forms, it is capable of embodiment in other forms without departing from the spirit and scope of the appended claims.

What is claimed is:

1. In a radio signaling system, the combination with a plurality of parallel antennæ, each staggered longitudinally a fraction of a wave length with respect to the others, a receiving circuit directly connected with one of said antennæ and by means of transmission lines with the other antennæ, means connected between said receiving circuit and said direct-connected antenna to equalize the magnitudes and shift the relative phases of the currents of that antenna and another of said antennæ, means to combine the currents from the said direct-connected antenna and the said other antenna and to reduce the resultant current by one half, another means to combine the resultant current with the current from the third antenna and means interposed between said other combining means and the transmission line of said third antenna to equalize the magnitudes and shift the relative phases of the currents from it and from the other antennæ.

2. In a radio signaling system, the combination with a plurality of pairs of parallel coterminous conductors, divided into a plurality of sections, all of said pairs being coterminous at the section junction points, means to connect all of the conductors of a section to ground at one end through a resistance representing the characteristic impedance of the section, means to connect to ground all of the conductors of the same section through the winding of a transformer, the other winding of which is connected across a pair of conductors of the adjacent section in the direction of the terminal apparatus, networks connected with certain of said pairs to equalize attenuation and shift phase, means to combine the currents from certain antennæ and to control the magnitude of the resultant current, and means to combine the said resultant current

with the current from another certain antenna.

3. In a radio signaling system, the combination with a sectionalized horizontal antenna array, each section comprising a plurality of coterminous, parallel pairs of conductors having means to ground all conductors in parallel to act as antennæ, one grounding means including the winding of a transformer by which the current created in that section by a wave may be impressed upon a pair of conductors of succeeding sections for transmission to a terminal circuit, and means associated with said terminal circuit to combine the currents from certain of said antennæ in desired phase and magnitude relations and to control the magnitude of the resultant current, and means to combine the resultant current with the current set up by the said wave in certain others of the said antennæ.

4. In a directive radio signaling system including an antenna array comprising more than two antennæ, equally spaced apart and staggered longitudinally by a predetermined distance with respect to the adjacent antennæ, the method of eliminating undesired currents which consists in changing the phase of the current in one of said antennæ so that it will be in phase with the current in another of said antennæ, combining the currents from the said one and said other of said antennæ, attenuating to a desired extent the current resulting from such combination, shifting by 180 degrees the phase of the attenuated current, and then combining the said attenuated current with the current set up in a third antenna of said directive signaling system.

5. In a directive radio signaling system including an antenna array comprising more than two antennæ, equally spaced apart and staggered longitudinally by a predetermined distance with respect to the adjacent antennæ, the method of eliminating interference from a predetermined direction which consists in changing the phase of the current set up in one of said antennæ by the interference from the predetermined direction so that that current will be in phase with the current set up by the same interference in another of said antennæ, combining the currents from the said one and the said other antennæ, attenuating to a desired degree the resulting current from said combination, shifting by 180 degrees the phase of the resulting current and combining the latter current with the current set up by said interference in the third antenna of said array whereby the effect of the interference from a known direction is substantially eliminated.

6. In a directive radio signaling system including an antenna array comprising more than two antennæ, equally spaced

apart and staggered longitudinally by a predetermined distance with respect to the adjacent antennæ, the method of eliminating interference from a predetermined direction which consists in changing the phase of the current set up in one of said antennæ by the interference from the predetermined direction so that that current will be in phase with the current set up by the same interference in another of said antennæ, combining the currents from the said one and the said other antennæ, attenuating to a desired degree the resulting current from said combination, shifting by 180 degrees the phase of the resulting current, combining the latter current with the current set up by said interference in the third antenna of said array, and shifting to a desired degree the current set up in said third antenna by said interference, so that that current and the said resulting current substantially neutralize, and eliminate the effect upon the received signal of interference from a predetermined direction.

In testimony whereof, I have signed my name to this specification this 21st day of August, 1928.

ARTHUR G. CHAPMAN.
